PRESS

Leslie S. Hubbert, Edison, Ohio, assignor, by
mesne assignments, to The Hydraulic Press
Corporation, Inc., Wilmington, Del., a corpora-
tion of Delaware

Application February 27, 1933, Serial No. 658,725

7 Claims. (Cl. 100—50)

My invention relates to presses and, in particular, to presses for pressing fruits, such as apples.

It is the object of my invention to provide a press which will compress the fruit yieldingly, disintegrate the fruit, impart to the fruit a final compression while containing the disintegrated pulp in a foraminous container, thereby subjecting the fruit to a first pressing operation while it is being macerated and disintegrated into juicy pulp and then to a second operation by which the juice is finally extracted from the pulp.

It is my object to contain the pulp so pressed within a bag so that it can be bodily removed from the press without spilling the contents of the bag.

It is a further object to provide means for sealing the bag after the juicy pulp has been introduced into the bag and holding it in sealed condition as the final pressing operation takes place to prevent the pulp making its exit out of the mouth of the bag.

It is an object to provide a hydraulic system for circulating fluid so that the presser of the initial pressing operation may be reciprocated; and may be permitted to return under the influence of extraneous mechanical means.

It is my object to provide in a single unitary structure a casing, motor pump and oil supply storage for the hydraulic system and the pressing apparatus with doors for introducing the fruits, such as apples, and for the removal of the pulp after it is pressed, and a spout for the delivery of apple juice, or whatever juice is extracted from the particular fruit.

It is a further object to provide the apparatus in units which can be assembled or disassembled as units to facilitate repair.

Referring to the drawings:

Figure 1 is a perspective of the complete machine ready for pressing;

Figure 2 is a similar view with the press chamber open, from which has been removed the press bag and with the trap door open through which is inserted the fruit to be pressed;

Figure 3 is a vertical section through the complete structure on the line 3—3 of Figure 1;

Referring to the drawings in detail, 1 is a foundation or base on which is mounted the driving motor 2. This motor is connected by its armature 3 through the coupling 4 to a hydraulic pump 5 which delivers fluid, such as oil, through the line 6 to the port 7 of the fitting 8 on the end of the ram cylinder 9, the other end of which is connected by the pipe 10 to the port 11 in the

plate 12 which forms the rear wall of the cylinder 13 containing the press ram piston 14 and piston rod 15. The pump is connected to the oil reservoir 16 in the base 1 by the pipe system 17. Any surplus oil in the system is supplied to or taken from the reservoir 16.

When the piston 18 is forced forwardly with its piston rod 19 in the cylinder 9, it uncovers at the end of its stroke the pipe 10 admitting the hydraulic pressure through the pipe 10 into the cylinder 13. This occurs when the feed plunger 20 has its arcuate face 21 brought adjacent to the surface 22 of the rotary cutter or macerator 23 which carries the knives 24.

Apples are introduced between the feed plunger 20 and the cutter 23 through the swinging door 25 pivoted at 26 on the macerator casing 27 in which the feed plunger 20 reciprocates. A hook 28 on the rear of the feed plunger 20 is connected by the cable 29 over the pulley 30 to a spring 31 mounted on the eye 32.

The casing 27 for the macerator 23 and feed plunger 20 is mounted by its flanges 33 and 34 on the walls 12 and 35 respectively by the bolts 36 and 37. This gives a broad, firm, spaced foundation for the macerator housing 27. The wall 12 carries a sleeve 36a for receiving the left hand end of the cylinder 9. This cylinder is provided with a packing 37a about the piston rod 19 adjacent the point of entry of the piston rod into the macerator casing 27 to prevent leakage.

The macerator or cutter 23 is mounted on an operating shaft 38 which is directly connected to and driven by an independent flanged motor 39. Instead of employing this independent motor 39, however, the shaft 38 may be driven by a flexible shaft, chain or gearing from the motor 2. Current is conducted to the motor 39 through wiring in the conduit 39a. The pulp descends through the passageway 40 into the interior of a cotton bag 41, the throat of which encircles the throat 42 forming the passageway 40. The rear of this bag throat 43 is held beneath the clip 44 and the front portion of the throat of the bag at 45 is held beneath the clip 46. The body of the bag depends in the space 47 between the foraminous press plates 48 and 49. The plate 49 is mounted on the end door 50 which is pivoted at 51 and retained in operative position by the latches 52 which are pivoted on the casing at 53.

The plate 48 is mounted on the presser head 54 carried on the end of the piston rod 15, to which it is pivoted at 55. This piston rod 15 with its presser head 54 is withdrawn to its initial position by the helical spring 56 connected to it at 57.

50 55

at one end and to the stationary abutment 58 at the other end which is carried on the sleeve 59 mounted on the wall 12.

The space 60 in front of the piston 14 communicates with the port 61 for draining any fluid which will accumulate in front of the piston 14.

The bag 41 which rests with its bottom upon the drain plate 62 that has the drain openings 63 is so arranged in the manner that it is supported that the sharp edge 64 of the head 54 will first withdraw the upper edge of the bag 43 and move it across the opening 40 to seal the pulp in the bag and then engage the wall 45 of the bag carrying it with the wall 43 into the horizontal position shown at 65. Thus, the bag is completely sealed and the exit of its pulp contents, from which the juice has been finally expelled by the presser 54, is prevented.

After the juice has run out down the inclined 20 passageway 66 over the lip 67, the latches 52 are lifted, the door 50 swings downwardly as shown in Figure 2 about the pivot 51 and the bag is lifted out where it can either be thrown away or its contents discharged.

25 The operation of the machine is controlled by suitable electric switches, which form no part of the invention. The motor runs through a complete cycle of operations which will be repeated as many times as necessary as the apples are fed one by one through the trap door 25. It may require one or more apples before the bag is filled with pulp.

30 The pressure exerted in the hydraulic system is automatically controlled by a spring loaded safety valve 68 which bypasses the fluid to the reservoir 16 when the maximum pressure has been reached.

35 The mechanism of the motor, pump, pressure cylinder, feed cylinder, pipe, relief valve, etc., is all encased in a stainless metal cover and all parts coming in contact with the apples or juice are made of stainless alloy. A pressure gauge located at 69 in the hydraulic system indicates the pressure being generated at all times.

40 45 The electric motor 39 which is directly connected with the grinder shaft and the electric motor 2 connected to the pump 5 are wired in parallel so that the turning of one switch starts both motors simultaneously.

50 It will be understood that I desire to comprehend within my invention such modifications as may be necessary to adapt it to varying conditions and uses.

55 It will be further understood that a number of apples may be stored in the chamber 27 at one time if desired.

Having thus fully described my invention, what I claim as new and desire to secure by Letters Patent, is:

60 1. In combination, a feed plunger, a hydraulic ram for operating said feed plunger, a macerator chamber therearound, a macerator at the end of said macerator chamber over a port in the chamber, means to operate said macerator, means to form a press chamber, one wall of which is movable, means to actuate said movable wall comprising a hydraulic ram, means to supply hydraulic pressure to said rams in succession whereby the fruit is first compressed and macerated and thereafter squeezed free of its juice, a bag suspended in the press chamber with its mouth surrounding the port through which the pulp flows from the macerator, and means on the 65 moving wall of the press chamber for successively 70 75

engaging the walls of the bag to detach them and close them with the pulp in the bag.

2. In combination, a feed plunger, a hydraulic ram for operating said feed plunger, a macerator chamber therearound, a macerator at the end 5 of said macerator chamber over a port in the chamber, means to operate said macerator, a press chamber having a portion movable into a plurality of positions, a pressing head adapted to move therein, means to actuate said pressing head comprising a hydraulic ram, means to supply hydraulic pressure to said rams in succession whereby the fruit is first compressed and macerated and thereafter squeezed free of its juice, and a bag suspended in the press chamber with its 10 mouth surrounding the port through which the pulp flows from the macerator, said movable chamber portion having bottom and side walls adapted to support said bag on the bottom and sides thereof selectively in one position in alignment with said pressing head and in another position for the removal of said bag, the space between the sides and bottom of said movable portion being open rearwardly to permit the engagement of the rearward wall of said bag by 15 said pressing head whereby to prevent the lateral distention of said bag during the pressing engagement of said pressing head therewith or during the moving of said movable portion into its 20 bag-removal position.

3. In combination, a feed plunger, a hydraulic ram for operating said feed plunger, a macerator chamber therearound, a macerator at the end of 25 said macerator chamber over a port in the chamber, means to operate said macerator, means to form a press chamber having a portion movable into a plurality of positions, a pressing head adapted to move therein, means to actuate said pressing head comprising a hydraulic ram, means to automatically supply hydraulic pressure to said 30 rams in succession whereby the fruit is first compressed and macerated and thereafter squeezed free of its juice, a bag suspended in a press chamber with its mouth surrounding the port through which the pulp flows from the macerator, said movable chamber portion having bottom and side walls adapted to support said bag on the bottom and sides thereof selectively in one position in alignment with said pressing head and in another position for the removal of said bag, and 35 an additional wall associated with said pressing head for successively engaging the walls of the bag to close the mouth thereof, said additional wall cooperating with said pressing head and with the walls of said movable chamber to form 40 a substantially complete enclosure for said bag.

4. In combination, a base having a fluid reservoir, a motor on said base, a pump on said base connected to the reservoir, a pair of hydraulic rams adapted to be successively operated by said 45 pump, a feed plunger connected to the first ram and operating in a macerator chamber, means to macerate the fruit between the said plunger and the end of the macerator chamber, a press chamber, means for detachably positioning a bag 50 within said press chamber adapted to receive the macerated fruit for pressing it, a pressing head moved by the second hydraulic ram, and a sealing member on said head and movable therewith to seal the neck of said bag prior to the 55 pressing engagement of said pressing head therewith.

5. In combination, a base having a fluid reservoir, a motor on said base, a pump on said base connected to the reservoir, a pair of hydraulic 60 65 70 75

rams adapted to be successively operated by said pump, a feed plunger connected to the first ram and operating in a macerator chamber, means to macerate the fruit between the said plunger and the end of the macerator chamber, a press chamber, means for detachably positioning a bag within said press chamber adapted to receive the macerated fruit for pressing it, a pressing head moved by the second hydraulic ram, and a sealing member on said head and movable therewith to seal the neck of said bag prior to the pressing engagement of said pressing head therewith, one wall of said press chamber being pivoted to enable the removal of the bag containing the compressed pulp in the chamber.

6. In combination, a base having a fluid reservoir, a motor on said base, a pump on said base connected to the reservoir, a pair of hydraulic rams adapted to be successively operated by said pump, a feed plunger connected to the first ram and operating in a macerator chamber, means to macerate the fruit between the said plunger and the end of the macerator chamber, a press chamber adapted to receive the macerated fruit for pressing it, one wall of which is moved by the second hydraulic ram and the other wall of which is pivoted to enable the removal of the compressed

pulp in the chamber, and means for detachably suspending a bag for receiving the pulp within said chamber, said pivoted wall having a shelf thereon to support the bottom of said bag and a foraminated back plate to support the back 5 thereof.

7. In combination, a base having a fluid reservoir, a motor on said base, a pump on said base connected to the reservoir, a pair of hydraulic rams adapted to be successively operated 10 by said pump, a feed plunger connected to the first ram and operating in a macerator chamber, means to macerate the fruit between the said plunger and the end of the macerator chamber, a press chamber adapted to receive the macerated fruit for pressing it, one wall of which is moved by the second hydraulic ram and the other wall of which is pivoted to enable the removal of the compressed pulp in the chamber, means for detachably suspending a bag for receiving the pulp 20 within said chamber, and means to seal the bag projecting from the movable wall of the press chamber, whereby the motion of the press wall seals the bag prior to the pressing engagement of said movable wall with said bag. 25

LESLIE S. HUBBERT.
